[57] CLAIM

The ornamental design for a vacuum cleaner nozzle, as
shown and described.

DESCRIPTION

FIG. 1 is a perspective view of the vacuum cleaner
nozzle showing our new design;

FIG. 2 is a top plan view thereof;

FIG. 3 is a bottom plan view thereof;

FIG. 4 is a front elevational view thereof;

FIG. 5 is a rear elevational view thereof; and

FIG. 6 is a right side elevational view, the left side
elevational view being a mirror image thereof.
